Primary Examiner — T Chase Nelson

(74) *Attorney, Agent, or Firm* — Banner & Witcoff, Ltd.

(57) **CLAIM**

The ornamental design for a shoe, as shown and described.

DESCRIPTION

FIG. 1 is a side view of a shoe showing my new design; FIG. 2 is a rear perspective view thereof; FIG. 3 is a rear view thereof; and, FIG. 4 is an opposite side rear perspective view thereof. The broken lines depicting the remainder of the shoe form no part of the claimed design.

1 Claim, 4 Drawing Sheets
